UNITED STATES PATENT OFFICE.

RICHARD WATSON, OF BLACKBURN, ENGLAND.

SHEDDING MOTION FOR LOOMS FOR WEAVING.

Application filed July 11, 1923. Serial No. 650,954.

To all whom it may concern:

Be it known that I, RICHARD WATSON, a British subject, residing at Blackburn, county of Lancaster, England, have invented certain new and useful Improvements in Shedding Motions for Looms for Weaving, of which the following is a specification.

This invention relates to shedding motions more particularly applicable for calico looms with a plain shed.

The object of the invention is to dispense with tappets and levers or treadles and to provide a positive oscillating motion to operate the healds alternately, and according to the invention an oscillating or rocking motion is imparted to a shaft carrying bosses to which the heald straps or connections are attached.

It is constructed with a crank wheel and connecting rod driven from a rotary part of the loom, a shaft and slotted lever rocked or oscillated by the connecting rod and a second rocking or oscillating shaft geared thereto carrying heald bosses by which the healds are operated.

The invention will be fully described with reference to the accompanying drawings in which sufficient of a loom is shown to illustrate the invention.

Fig. 1. is a front elevation of the improved apparatus.

Fig. 2 is an end elevation.

Fig. 3 is a perspective view of bracket E detached.

Fig. 4 is a perspective view of gear wheel g detached.

Fig. 5 is a perspective view of connecting rod C detached.

Fig. 6 is a perspective view of guide bracket F¹ detached.

Fig. 7 is a perspective view of slotted lever H detached.

Fig. 8 is a perspective view of the guide bracket F detached.

In carrying out the invention on the side or gable end of the loom a crank wheel A is mounted to rotate on a suitably placed stud or shaft a and driven by a wheel B from the ordinary crank shaft b. The wheel A is fitted with a crank pin a' which by being bolted in one of several holes a² a³ therein may be set at any desired distance from the centre to vary the throw as required, and a connecting rod C is carried on the crank pin a'.

The connecting rod C is built up of two side rods c with a number of bowls or runners d' d² d³ d⁴ d⁵ d⁶ at its free end mounted to rotate upon a transverse bar d bolted between the two side rods c. The bowls or runners d' to d⁶ receive a to and fro movement from the crank pin a' as the wheel A rotates.

A bracket E bolted to the loom gable carries one or two guide brackets F, (preferably two to give a steady movement) with guide races f² f³ in which the bowls or runners d' d² and d⁶ and d⁶ travel as they are rocked to and fro by the crank pin a'. The guide races are of the shape shown and give a corresponding inclined or horizontal movement to the end of the connecting rod C. The guide races are each formed with two faces f f' so that each bowl bears against one face only of the race to avoid friction and the races are of such a shape as to cause the free end of the connecting rod to travel at an inclination to the horizontal at each end of its traverse, to impart a "dwell" at each end of the forward and backward stroke.

A shaft G passes through the guide brackets F F' carrying at one end a pinion wheel g, and affixed to it at or near the centre between the guide races is a slotted lever H. The two centre bowls d³ and d⁴ of the connecting rod C engage with the slot h of the lever H imparting a positive rocking or oscillating motion to the shaft G as the rod C moves to and fro with a dwell at each end as the bowls travel the inclined parts of the faces f f'.

A second shaft K extends across the loom and is geared to the rocking shaft G by a pinion g' and to this shaft the oscillating or rocking motion of the shaft G is imparted. It carries the heald bosses k to which the heald straps k' are connected.

The dwell of the oscillating shaft G at each stroke of the connecting rod C imparts the necessary dwell to the heald M at each pick. The dwell of the shaft K and healds M can be varied or adjusted by altering the crank pin a' and the throw of the connecting rod C, thus more or less dwell is obtained at will, and the "lift" of the healds can also be varied by changing the ratio of the gear wheels g and g' by which the two shafts G and K are geared together.

The motion may be placed either below or above the healds, the healds being con-

nected by straps passing over a roller, or two such motions working synchronously may be employed one below and the other above the healds.

5 What I claim as my invention and desire to protect by Letters Patent is:—

1. A shedding motion for looms comprising in combination a crank wheel driven from a rotary part of the loom, a connecting rod, fixed guide brackets to control and guide the path of the free end of the connecting rod, races in the fixed guide brackets, a shaft and slotted lever oscillated by the connecting rod, the races in the guide brackets being inclined at the ends to provide a dwell for the shaft, a second oscillating shaft geared to the first shaft, heald bosses on the second shaft by which the healds are operated and means for varying 20 the dwell of the shafts and the lift of the healds.

2. A shedding motion for looms comprising in combination a crank wheel, driven

from a rotary part of the loom, a connecting rod built up of two side rods, a transverse bar at the free end of the connecting rod a plurality of runners upon the transverse bar, races in fixed guide brackets engaged by said runners, a shaft and slotted lever oscillated by the connecting rod, the races 30 in the guide brackets being inclined at the ends to provide a dwell for the shaft, a second oscillating shaft geared to the first shaft, heald bosses on the second shaft by which the healds are operated and means 35 for varying the dwell of the oscillating shafts and the lift of the healds.

In testimony whereof I have hereunto set my hand in presence of the subscribing witnesses.

RICHARD WATSON.
